UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN, A CORPORATION OF MICHIGAN.

FEEDING-WEB TO PRINTING-PRESSES.

1,359,863.

Specification of Letters Patent. Patented Nov. 23, 1920.

Application filed March 6, 1920. Serial No. 363,850.

To all whom it may concern:

Be it known that I, HENRY F. BECHMAN, a citizen of the United States, residing at Battle Creek, in the county of Calhoun and 5 State of Michigan, have invented certain new and useful Improvements in Feeding-Webs to Printing-Presses; and I hereby declare that the following is a full, clear, and exact description thereof, reference being 10 had to the accompanying drawings, which form part of this specification.

This invention relates to rotary web printing presses and has particular reference to the type of single page tubular plate printing presses shown in my Patent No. 867,230 15 of 1907, but is applicable to any web printing presses using narrow two page long plate cylinders, and requiring a multiple of perfecting mechanisms to produce a larger 20 number of pages. In such presses as ordinarily constructed only narrow, or two-page-wide webs can be used, and this ordinarily requires a separate paper feeding and handling mechanism for each perfecting mechanism in the press; and therefore a large 25 number of small web rolls have to be handled in publishing an edition of any considerable size.

The object of the present invention is to 30 reduce the number of paper feeding mechanisms required for such presses, and lessen the number of web rolls to be handled, by providing means whereby wide webs can be utilized, and the web can be fed from such wide web roll slit longitudinally and the 35 separate sections of such web respectively directed to separate printing mechanisms to be perfected, each web roll supplying two or more perfecting mechanisms.

40 In accordance with the present invention each four page wide web roll is arranged at one end of the press with the axis of the web roll parallel with the plate and impression cylinders in the perfecting mechanisms; and means is provided for slitting the web longitudinally and one section of the slit web is led in a straight line directly to one of the perfecting mechanisms; while the other section of the web is diverted by 45 means of angle bars and led directly to another perfecting mechanism; both sections of the printed web being thereafter assembled at the folder in the usual manner if desired.

The accompanying drawings illustrate 55 diagrammatically part of a printing press and web handling mechanism therefor in accordance with the invention; and I will describe the invention with reference thereto, to enable others skilled in the art to 60 adapt and use the same; and then set forth in the claims the essentials of the invention and novel features of construction and novel combinations of parts for which protection is desired. 65

In said drawings Figure 1 is a diagrammatical side elevation of a rotary printing mechanism and equipped with my novel web feeding means.

Fig. 2 is a top plan view of Fig. 1. 70

In the drawings A and B represent two rotary perfecting printing mechanisms, preferably of the single page tubular type, as described in my aforesaid patent; each comprising plate cylinders 1, 1^a and co-operating impression cylinders 2, 2^a. The plate cylinders, in the example shown, are adapted to carry only two page plates end to end, and therefore can only print a web two pages wide. 80

A four-page wide roll of web W may be mounted on suitable supports, in the usual manner, at one end of the press; and the web may be fed from the roll in the usual manner; as by feed rolls 3, 3^a. The web roll W is so set that its axis is parallel with the axes of the plate and impression cylinders, and one end of the web roll is in line with the ends of the plate and impression cylinders at one side of the press; while the other end of the web roll projects beyond the ends of such plate and impression cylinders at the opposite side of the press. 90

The wide web from such roll may be led over any suitable guides past a slitter S, 95 operated in the usual manner, by which the web is divided into two longitudinal sections w' and w². The section w' of the web passes straight from the web roll, past the slitter and over guides g' g', to and between the plate and impression cylinders in the printing mechanism A; and thence over a guide g² to the folder (not shown) at the end of the press; or if desired to a second printing mechanism (not shown) to be printed 100 in colors. 105

The section w² of the web passes from the slitter S to and over a guide g³, then to and

over an angle bar 4 arranged at an angle of 45° to the web roll and plate and impression cylinders by which the section w^2 is diverted at right angles to the section w' and toward 5 the section w' . The section w^2 is then passed over a second angle bar 4^a arranged parallel with the angle bar 4, but at the opposite side of the press and directly over the section w' of the web, whereby the section 10 w^2 is diverted back into a path parallel with (and in the example shown above) the section w' ; thence the section w^2 passes beyond the printing mechanism A to a guide g^4 by which it is directed to and between the plate 15 and impression cylinders in the printing mechanism B; thence it passes over a guide g^5 to the folder (not shown), or if desired to a second perfecting mechanism (not shown) to be printed in colors.

20 It will be seen that in this invention both sections w' , w^2 of a wide web are preferably brought directly into alinement; then each section of the web is passed to a separate printing mechanism; or mechanisms, 25 which are preferably arranged parallel and in a straight line.

The particular printing mechanisms, or the number of printing mechanisms through which the sections w' , w^2 of the web are led 30 form no part of the present invention.

By this invention two or more narrow printing mechanisms, arranged in line, can be simultaneously supplied with sections of web from a single roll of wide web arranged 35 parallel with the axes of the cylinders in the printing mechanisms; and by this invention one web controlling and feeding mechanism will suffice to supply sections of web from a wide roll to different alined printing 40 mechanisms, ordinarily requiring two distinct narrow web rolls and two feeding mechanisms to supply them with web.

In the drawings the roll of web W is illustrated as being four pages wide, but of 45 course it might be of any desired width, and be divided into any desired number of longitudinal sections—for example, if it is desired to print a web only one page wide in one of the printing mechanisms then a web 50 roll three pages wide could be used and one section instead of being two pages wide could be one page wide; therefore I do not consider the invention restricted to the employment of webs an even number of pages 55 wide; nor to having the web sections of the same width.

What I claim is:

1. In a printing press having a plurality of narrow printing mechanisms; means for 60 supporting a roll of web wider than the printing mechanisms at one end of the press, one end of the web roll being approximately in line with the end of the printing mechanism at one side of the press, and the other 65 end of the web roll projecting beyond the

other end of such printing mechanism; means for slitting the web; means for directing one section of the web direct from the web roll to one of the printing mechanisms; means for deflecting the other section 70 of the web between the web roll and the printing mechanism; and means for directing the diverted section of the web to the other printing mechanism; substantially as described. 75

2. In a printing press having narrow rotary printing mechanisms; means for supporting a wide web roll at one end of the press; one end of the web roll being approximately in line with the ends of plate and impression cylinders in one printing mechanism, and the other end of the web roll projecting beyond the other ends of such cylinders; means for slitting the web; means for directing one section of the web straight 80 to the said printing mechanism; angle bars over which the other section of the web is led and by which it is diverted; and means for directing the diverted section of the web to another printing mechanism, substantially as described. 85

3. In a printing press having a plurality of narrow printing mechanisms arranged parallel and in line; means for supporting a roll of web wider than the printing mechanisms at one end of the press and parallel with the printing mechanisms, one end of the web roll being approximately in line with the ends of the printing mechanisms at one side of the press, and the other end 90 of the web roll projecting beyond the other ends of the printing mechanisms at the opposite side of the press; means for slitting the web; means for directing one section of the web straight from the web roll to one 95 of the printing mechanisms; means for deflecting the other section of the web between the web roll and the printing mechanisms so as to bring such section of the web parallel with the first section of the web; and means for directing the diverted section of the web to the other printing mechanism; substantially as described. 100

4. In a printing press having two narrow rotary printing mechanisms arranged in line; means for supporting a wide web roll at one end of the press parallel with the plate and impression cylinders in the printing mechanisms; one end of the web roll being approximately in line with the ends of the plate and impression cylinders at one 110 side of the press, and the other end of the web roll projecting beyond the ends of the cylinders at the opposite side of the press; means for slitting the web; means for directing one section of the web straight to one of the printing mechanisms; angle bars over which the other section of the web is led and by which it is diverted into parallelism with the first section of the web; and 115

means for directing the second section of the web after being so diverted to another printing mechanism, substantially as described.

5. In combination a printing press having two two-page wide rotary printing mechanisms arranged in line; and means for supporting a four-page wide web roll at one end of the press parallel with the plate and impression cylinders in the printing mechanisms, one end of the web roll being in line with the ends of the plate and impression cylinders at one side of the press and the other end of the web roll projecting beyond the ends of the cylinders at the op-

posite side of the press; with means for 15 slitting the web; means for directing one section of the web straight to one of the printing mechanisms; a pair of angle bars over which the other section of the web is led and by which it is diverted into parallelism with the first section of the web; and means for directing the second section of the web, after being so diverted, to the second printing mechanism, substantially as described. 20

In testimony that I claim the foregoing as my own, I affix my signature.

HENRY F. BECHMAN.
